P. D'H. DRESSLER.

TUNNEL KILN AND METHOD OF OPERATING SAME,
APPLICATION FILED FEB. 26, 1920.

1,369,330.

Patented Feb. 22, 1921.

Inventor
Philip D'Wressler
John E. Hubbell
By his Attorney

UNITED STATES PATENT OFFICE.

PHILIP D'H. DRESSLER, OF ZANESVILLE, OHIO, ASSIGNOR TO AMERICAN DRESSLER
TUNNEL KILNS, INC., OF NEW YORK, N. Y., A CORPORATION OF NEW YORK.

TUNNEL-KILN AND METHOD OF OPERATING SAME.

1,369,330.

Specification of Letters Patent. Patented Feb. 22, 1921.

Application filed February 26, 1920. Serial No. 361,554.

To all whom it may concern:

- Be it known that I, PHILIP D'H. DRESSLER, a subject of the King of Great Britain, and resident of Zanesville, in the county of 5 Muskingum and State of Ohio, have invented certain new and useful Improvements in Tunnel-Kilns and Methods of Operating Same, of which the following is a specification.
- 10 My invention relates to continuous tunnel kilns of the type adapted for use in the manufacture of clay products and in annealing glass and metals, and for other purposes. The general object of the invention 15 is to provide a simple and effective method of, and apparatus for overcoming the tendency for the ends of such a kiln to become too hot.

The various features of novelty which 20 characterize my invention are pointed out with particularity in the claims annexed to and forming a part of this specification. For a better understanding of this invention however, its advantages and the objects 25 attained with its use, reference should be had to the accompanying drawings and descriptive matter in which I have illustrated and described in some detail embodiments of my invention.

30 Of the drawings:

Figure 1 is a plan view in section of a tunnel kiln.

Fig. 2 is a vertical section taken on the line 2-2 of Fig. 1.

35 Fig. 3 is a partial plan in section on the line 3-3 of Fig. 2.

Fig. 4 is a transverse section on the line 4-4 of Fig. 2 and

40 Fig. 5 is a transverse section on the line 5-5 of Fig. 2.

The kiln shown in the drawings is of the well known Dressler tunnel kiln type and comprises an inclosed chamber A in which is located a track B for goods carrying cars E which enter the kiln at one end and leave at the opposite end. As shown the entrance end of the chamber A is normally closed by a door F, and the exit end by a door G, though one or both of these doors may 45 sometimes be omitted. At each side of the pathway for the goods or wares of the cars E are combustion chambers C. The latter have flue passages D in their walls whereby a transverse convection current circulation 50 of the kiln atmosphere is set up along the 55

lines indicated by the arrows in Fig. 4. The combustion chambers C do not extend to either end of the chamber A. At one end each combustion chamber C is connected to the adjacent ends of a group of tubes H 60 which extend in alinement with the combustion chamber to the exit end A² of the chamber A, and are there connected to a header H' which receives atmospheric air through the inlet H². The opposite end of each combustion chamber C is connected to tubes I which form a longitudinal extension of the combustion chamber and are connected at their ends remote from the latter to a header I'. Each header I' is provided with an outlet J 70 connected to a stack J'. Combustible gas is supplied to each combustion chamber C at the end of the latter to which the pipes H are connected as by means of a gas supply pipe K. 75

In the normal intended operation of the kiln shown in the drawings, the air supplied to the combustion chambers through the pipes H, and the gas supplied through the inlets K unite in combustion in the combustion chambers and the burning gases and products of combustion flow through the combustion chambers and pipes K to the stack J'. The goods entering the chamber A at A' are progressively heated up as they 85 move through the preheating zone containing the pipes I and the high temperature zone containing the combustion chambers C and are then cooled down as they move through the cooling zone of the chamber in 90 which the pipes H are located. The cooling of the goods causes the air in the pipes H to be raised to a high temperature desirable for maintaining efficient combustion in the combustion chambers C. In so far as above described the kiln illustrated presents nothing 95 now novel with me.

In the use of a tunnel kiln, whether of the muffle type such as that shown by way of example in the accompanying drawings, or 100 of the open fired type, difficulty is frequently experienced, because of a tendency of the entrance end of the kiln to become too hot at its top. I have found that this difficulty can be successfully overcome, or 105 avoided by suitably injecting cold air into the entrance end of the kiln along the roof of the kiln chamber. I believe that the tendency to overheating at the top of the entrance end of a tunnel kiln is due to a 110

convection current circulation of the kiln atmosphere, upward in the hotter central portion of the kiln and then along the top of the kiln chamber toward the entrance 5 end of the kiln with a return flow of cooler air along the bottom of the kiln, and that the desirable result which I obtain by a suitable injection of cool air into the end of the kiln is due to a modification by the injected 10 air of the convection current circulation referred to.

In the apparatus shown in the drawings the air injected into the top of the entrance end A' of the kiln is supplied by a blower 15 L connected to a metal duct or delivery trunk M located in the kiln chamber adjacent the roof of the latter and terminating in a discharge mouth M'. The latter is shaped to deliver a flat wide horizontal 20 stream of air directed away from the entrance end of the kiln along the roof of the kiln chamber. In operation I believe this stream engages the oppositely flowing convection current stream of the kiln atmosphere 25 approaching the entrance end of the kiln with the result that both streams are deflected downward to the bottom of the kiln. At the bottom of the kiln part of the downwardly deflected air turns and flows 30 along the bottom of the kiln chamber back toward the center of the kiln and part flows toward the entrance end of the kiln where it passes out into the atmosphere through cracks about the door or leakage ports 35 especially provided for the purpose. The circulation just described is indicated by the arrows applied to Fig. 2. In a kiln of the particular type disclosed wherein there is no forced flow of the kiln atmosphere 40 which masks or materially modifies the convection current tendency of the kiln atmosphere, the exit end of the kiln has the same tendency as the entrance end to become too hot at the top, and this tendency 45 may be overcome in the same way at each end of the kiln. I, therefore, provide at the exit end of the kiln a blower LA and delivery duct MA constructed and operating like the blower L and duct M. With the 50 blowers L and LA at the opposite ends of the tunnel it is possible to put the main interior of the kiln under a pressure slightly above that of the atmosphere without creating objectionable currents in the kiln atmosphere. This increase of pressure is desirable 55 in some cases. It insures that any leakage through the walls of the combustion chambers shall be from the kiln chamber into the combustion chambers and not in 60 the opposite direction. The effect of the discharges through the ducts M and MA, and the changes in the circulation of the kiln atmosphere made thereby is to appreciably reduce the temperature at the ends 65 of the kiln particularly at the top and to

equalize the temperatures at different levels in the end of the kiln and to some extent in the body of the kiln chamber. The reduction in the kiln and end temperatures thus obtained is very desirable in handling 70 some kinds of wares and in some cases permits of a shorter kiln than would otherwise be required. The changes in the circulation of the kiln atmosphere in the body portion of the kiln chamber produced by 75 the blowers L and LA make it somewhat easier to keep up the desirable high temperature there. It will be understood, of course, that the air discharged by the ducts M and MA must be adjusted, as by giving 80 the blowers L and LA the proper speed, to arrest the opposing convection currents at the proper points in the kiln chamber and in particular must not be powerful enough to materially modify the normal convectional circulation in the central portion of the kiln chamber. It is obvious, of course, that where the kiln atmosphere is not composed of air but of some other gaseous substance, such substance may be blown into 85 the kiln through the ducts M and MA. 90

While in accordance with the provisions of the statutes, I have illustrated and described the best embodiments of my invention now known to me, it will be apparent 95 to those skilled in the art that changes may be made in the form of my invention as set forth in the appended claims without departing from its spirit, and in particular it is to be understood that in some cases and 100 particularly with certain type of kilns it may be desirable to maintain a cold air barrier at one end only of the kiln chamber.

Having now described my invention, what I claim as new and desire to secure by Letters Patent, is:

1. The method of operating a tunnel kiln which consists in maintaining an atmosphere formed by a hot body of gaseous material in a central portion of the kiln chamber 110 without substantial movement of said atmosphere except for convection current circulation thereof, and blowing gaseous material into the end of the kiln along the top of the kiln chamber so as to create a downward flow of the kiln atmosphere between the end and center of the kiln with a return flow along the bottom of the kiln toward the kiln end, and the escape therefrom of the excess gaseous material passed into 115 the kiln chamber whereby the maintenance of an unduly high top temperature in the end of the kiln by reason of the convection current circulation of the kiln atmosphere is prevented.

2. In a continuous tunnel kiln the combination with the kiln chamber and means for heating it, of means for blowing a gaseous substance into the entrance end of the kiln in a stream directed toward the opposite 120

end of the chamber and flowing along the top of the latter.

3. In a continuous tunnel kiln the combination with the kiln chamber and muffle heating provisions therefor, of means for blowing a gaseous substance into one end of the kiln chamber in a stream directed toward the opposite end of the kiln chamber and flowing along the top of the latter.
- 10 4. In a continuous tunnel kiln, the combination with the kiln chamber and muffle heating provisions therein, of means for maintaining the pressure of the atmosphere

of the kiln chamber above that of the external atmosphere.

5. In a continuous tunnel kiln the combination with the kiln chamber and means for heating it, of means for blowing a gaseous substance into each end of the kiln chamber in a stream directed toward the opposite end of the kiln chamber and flowing along the roof of the latter.

Signed at Columbus in the county of Franklin and State of Ohio this 18th day of Feb. A. D. 1920.

PHILIP D'H. DRESSLER.
